UNITED STATES PATENT OFFICE.

HENRY WEINHAGEN, OF HOBOKEN, NEW JERSEY.

THERMOMETER-TUBE.

SPECIFICATION forming part of Letters Patent No. 233,586, dated October 19, 1880.

Application filed July 19, 1880. (No model.)

To all whom it may concern:

Be it known that I, HENRY WEINHAGEN, of Hoboken, in the county of Hudson and State of New Jersey, have invented certain new and useful Improvements in Thermometer-Tubes, of which the following is a specification.

The object of my invention is to produce a thermometer-tube wherein the appearance of the column of mercury and the graduations of the thermometric scale marked thereon will be enlarged or magnified so that they can be readily seen, and, moreover, to so construct the tube as to preclude it from rolling.

The invention consists in a thermometer-tube having a flat bore, a flat back, and sides forming acute angles with said back and converging toward and joining each other at an acute angle opposite said flat bore, so as to form a prismatic front, said tube being not liable to roll, and the flat bore and prismatic front contributing to conspicuously display the column of mercury.

In the accompanying drawings, Figure 1 is a face view of a thermometer-tube embodying my invention, and Fig. 2 is a transverse section of the same upon an enlarged scale.

Similar letters of reference designate corresponding parts in both figures.

The thermometer-tube is triangular in shape, and has a flat back, A, which will rest against any support on which it may be placed or to which it may be attached, and will preclude it from rolling thereon. It also forms a surface on which the graduation of the thermometric

scale can be easily and accurately marked by scratching, etching, or otherwise.

B and C designate, respectively, the two sides of the tube, which join the back at acute angles, and which converge toward the front and join each other at an acute angle opposite the bore D. The tube is made as sharp as possible at its junction, and forms a prismatic portion or front, which spreads or laterally enlarges the appearance of the column of mercury or like material in the bore and the thermometric graduations, and enables them to be seen without trouble. The bore is flat or elliptical, and arranged with its broad side toward the front, so as to be as prominently in view as possible, and contributing, with the prismatic front, to prominently display the column of mercury. The prismatic front and the flat bore together serve to render the column of mercury, even when very small, very perspicuous.

What I claim as my invention, and desire to secure by Letters Patent, is—

A thermometer-tube having a flat bore, a flat back, and sides forming acute angles with said back, and converging toward and joining each other at an acute angle opposite said flat bore, so as to form a prismatic front, said tube being not liable to roll, and the flat bore and prismatic front contributing to conspicuously display the column of mercury, substantially as specified.
